UNITED STATES PATENT OFFICE.

FRIEDRICH WOLFF, OF PARIS, FRANCE.

DESIGN FOR AN ADVERTISING SIGN.

Application filed November 5, 1928, Serial No. 28,760, and in Austria July 12, 1928. Term of patent 7 years.

To all whom it may concern:

Be it known that I, FRIEDRICK WOLFF, a citizen of the Republic of Austria, residing in Paris, France, have invented a new, original, and Ornamental Design for an Advertising Sign, of which the following is a specification.

The figure is a side view of the article showing the new design.

I claim:—

The ornamental design for an advertising sign as shown.

In testimony whereof I have hereunto set my hand.

FRIEDRICH WOLFF.
